UNITED STATES PATENT OFFICE.

HENRY GALLAGER, OF SAVANNAH, GEORGIA.

CAR-COUPING.

SPECIFICATION forming part of Letters Patent No. 431,768, dated July 8, 1890.

Application filed May 9, 1890. Serial No. 351,195. (No model.)

To all whom it may concern:

Be it known that I, HENRY GALLAGER, residing at Savannah, Chatham county, and State of Georgia, have invented a new and Improved Car-Coupling, of which the following is a specification.

My invention relates generally to car-couplers, and particularly to that class thereof known as "twin-jaw" couplers, and has for its object to provide a coupler of this class that shall be automatic in some of its operations; and it consists of a minimum number of simple parts.

With these objects in view my invention consists in the peculiar construction of parts and the novel combination or arrangement of the same, such as shown in the accompanying drawings, and hereinafter fully explained.

In the drawings forming a part of this specification, Figure 1 is a perspective view of my coupler as applied to a car. Fig. 2 is a top plan view of two couplers coupled, and Fig. 3 is a transverse vertical section of my coupler.

In my improved coupler the draw-bar A is of the usual or any preferred construction, and may be secured to the car in any suitable manner. The outer or forward end of the draw-bar is provided with the head B, which head consists of fixed jaws C C', rigid with the draw-bar and forming the throat of the head, and a movable jaw or section D, the latter section being, for convenience of description, termed the "shoulder-section," it forming the engaging-shoulder of the head. This section D is movable transversely to the direction of length of the coupler, and preferably vertically, as shown, it being moved up to release the coupling and down to position to form a part of the hook or jaw C'. The jaw C is curved outwardly, as shown, to facilitate the entrance of the opposite coupling-shoulder. The jaw C' projects longitudinally forward from the draw-bar, and in its inner side is formed the vertical dovetailed recess c opening into the throat of the head, said recess passing entirely through the said jaw and being adapted to receive the stem or rib D', formed integral with the movable shoulder-section D, whereby said shoulder is capable of a vertical movement in the jaw C'. The shoulder-section extends transversely to

the direction of length of coupler, preferably inward, and is somewhat hook-shaped on its inner side, as shown, whereby a positive coupling is effected with the mating shoulder-section of the opposite draw-head. The shoulder-section D is of a thickness from top to bottom equal to the head B; but the stem or rib D' projects a short distance below the lower face of said shoulder-section, which projection portion serves to steady the shoulder when in an elevated position. The projecting portion of the stem or rib D' has sufficient lateral play in the recess c to permit the elevated shoulder-section to be moved sidewise, so that its lower face will rest upon the upper face of the jaw C'. In this manner the shoulder-section is held in an elevated position to allow the shoulder-section of the opposite coupler to be inserted in the head B, and when the opposite shoulder contacts with the coupler whose shoulder is elevated, the jar is sufficient to dislocate the elevated shoulder, which will descend by its own weight, and thus automatically effect the coupling. To limit the downward movement of the shoulder-section, the upper end of the stem or rib D' is provided with a head or cap E, and to limit its upward movement the downwardly-projecting portion of the stem is provided with a laterally-extending set-screw F, said screw working in a vertical groove G, formed in the inner face of the recess c, and extending from the lower side of the jaw C' to about midway its height. The cap E is provided with an aperture e, in which is secured a chain e', by means of which the shoulder-section is elevated. The chain e' is so arranged that the shoulder can be elevated from either side or top of the car. The shoulder-section D is provided with a horizontal mortise d, to permit the insertion of an ordinary link, and the vertical bore d' is adapted to receive the ordinary pin. By this construction my improved coupler is equally well adapted for coupling with ordinary couplers now in use.

In practice the draw-bar A and head B, consisting of the jaws C and C', are all cast in one piece, and the shoulder-section D, stem or rib D', and cap E are all formed in one piece. From this it will be seen that my coupler consists, essentially, of two parts only,

and those parts of such simple and durable construction that the coupling is cheap, easily constructed, set, and operated.

Having thus described my invention, what 5 I claim, and desire to secure by Letters Patent, is—

1. In the herein-described car-coupler, the combination, with the draw-bar having a head consisting of the rigid jaws forming the throat 10 of the same, of a vertically-movable shoulder-section sliding in one of the jaws, substantially as and for the purpose described.

2. In a coupler, the combination of a draw-bar having the head consisting of the jaws C 15 and C', the jaw C' being recessed and a vertically-movable shoulder-section sliding in said jaw C', substantially as shown and described.

3. In a coupler, the combination, with a draw-bar having the head consisting of the 20 jaws C and C', the jaw C' being recessed, of a shoulder-section having a rib or stem working in said recess, and a cap upon the upper end of said rib to which the elevating mechanism is attached, substantially as shown and 25 described.

4. In a coupler, the combination, with a

draw-bar having a head formed of the jaws C and C', the jaw C' being recessed, of the shoulder-section provided with a rib or stem sliding in said recess, a cap upon the upper end 30 of the same to limit the downward movement of the shoulder, and to which the elevating mechanism is attached, and a stop upon the lower end of said rib or stem, substantially as shown and described.

5. In a coupler, the combination, with a draw-bar having a head formed of the jaws C and C', the jaw C' being recessed, as described, of a hook-like shoulder-section having a rib or stem sliding in said recess, said shoulder 40 having a horizontal mortise and vertical bore for ordinary coupling-links, a cap upon the upper end of the rib or stem to limit its downward movement, and to which the elevating mechanism is attached, a laterally-projecting 45 stop upon the lower end of said rib, said stop working in a groove in the inner face of the recess, substantially as shown and described.

HENRY GALLAGER.
